BICYCLE STEERING POST

Ruben L. Pawsat, Maysville, Ky., assignor to Wald Manufacturing Company, Incorporated, Maysville, Ky., a corporation of Kentucky

Filed Mar. 4, 1965, Ser. No. 84,083

Term of patent 14 years

(Cl. D90—9)

FIG. 1 is a side plan view of a bicycle steering post, embodying my new design. The opposite side of said steering post is a duplicate of the side illustrated.

FIG. 2 is a rear elevational view thereof.

FIG. 3 is a top plan view thereof.

FIG. 4 is a bottom plan view thereof.

The essential features of my design reside in the combination on the bicycle steering post disclosed, of the offset angle arm, clamping ring, and bolt wherein a free edge of the clamping ring is substantially parallel to the longitudinal axis of the arm and in spaced parallel relation to the opposed edge on the arm, as shown in full lines.

I claim:

The ornamental design for a bicycle steering post, as shown and described.
